L. L. MILLER

NUT SCREENING APPARATUS

Filed Oct. 9, 1923

INVENTOR.
L.L. Miller
BY *George Webster*
ATTORNEY

UNITED STATES PATENT OFFICE.

LAURENCE L. MILLER, OF RIPON, CALIFORNIA.

NUT-SCREENING APPARATUS.

Application filed October 9, 1923. Serial No. 667,440.

To all whom it may concern:

Be it known that I, LAURENCE L. MILLER, a citizen of the United States, residing at Ripon, county of San Joaquin, State of California, have invented certain new and useful Improvements in Nut-Screening Apparatus; and I do declare the following to be a full, clear, and exact description of the same, reference being had to the accompanying drawings, and to the characters of reference marked thereon, which form a part of this application.

This invention relates to improvements in devices for separating almonds from their hulls and other accompanying foreign matter after they have been passed through the hulling machine.

The principal object of my invention is to provide a screening apparatus which will automatically cause the separation of the hulls, etc., from the almonds, without any bruising of the latter, and from which the nuts will be discharged in a very clean condition, so that subsequent hand-picking is reduced to a minimum.

I have also provided means for causing undersized nuts and any meats, as well as unthreshed nuts, to be automatically segregated from the normal size hulled nuts, so that the subsequent sorting will be unnecessary.

As another object of the invention I have provided adjustment means for the screens so that nuts of different sizes and thicknesses, depending on the brand of nut grown and handled, may be treated with equal facility in the one apparatus, although of course at different times.

A further object of the invention is to produce a simple and inexpensive device and yet one which will be exceedingly effective for the purposes for which it is designed.

These objects I accomplish by means of such structure and relative arrangement of parts as will fully appear by a perusal of the following specification and claims.

In the drawings similar characters of reference indicate corresponding parts in the several views:

Fig. 1 is a longitudinal section of the apparatus.

Fig. 2 is a cross section thereof.

Fig. 3 is an enlarged fragmentary plan of an upper screen structure.

Fig. 4 is an enlarged fragmentary section of the same.

Fig. 5 is an enlarged fragmentary section of the lower screen structure.

Referring now more particularly to the characters of reference on the drawings, the numerals 1 and 2 denote vertically spaced pairs of horizontal frame structures, rigidly connected together by vertical members 3, which are supported from a base 4 by means of substantially vertical and horizontally flexible spring members 5 such as are commonly used in shaker-table construction.

The frames are reciprocated horizontally by means of horizontal rods or arms 6 connected to an eccentric drive of short throw. This latter feature is not shown, since the use of such is well known, and of itself forms no part of my invention. This drive arrangement imparts a jerky up-and-down movement to the frames, besides a longitudinal movement, causing the nuts, etc., to gradually travel from one end to the other of the screens now to be described.

Fixed on and under the frames 1 and covering the space therebetween for the greater portion of the area thereof is a metal sheet 7 having throughout its area a plurality of somewhat closely spaced holes 8. These holes are neither round nor truly oval, but are shaped to be as near as possible symmetrical with the shape of an almond, the major axes being transversely of the sheet.

Directly under the screen-sheet 7 and in contact therewith is another similar sheet 9 having holes 10 the same size as the holes 8 and aligned therewith transversely of the screen, but arranged to be somewhat overlapped by the latter so as to alter the size of the openings through the screens while maintaining them symmetrical with the general shape of almonds at all times, as will be evident. This screen structure can therefore be used to handle nuts of any size.

The screen-sheet 9 is slidably mounted for movement longitudinally of the screen 7, so as to enable the size of the openings therethrough to be altered for the purpose above stated. A screw 12 is fixed on one end of the sheet 9 to enable it to be readily moved by the operator.

The screen 9 is held in contact with the screen 7 by any suitable means, such as bolts 13 passing through the frames 1 and

through longitudinal slots 14 in the sheet 9, springs 15 being about said bolts between the frames 1 and the bolt-heads thereabove. To prevent sagging of the screens between the frames cross-supports 1^a extend thereunder at suitable intervals.

As previously stated, the screens 7 and 9 do not extend from end to end of the frames 1, but only from one end thereof to a point short of the other end. Mounted on and under the frames 1 beyond the screen sheets and to the adjacent end of said frames are transversely spaced rods 16, disposed in evenly spaced relation throughout. Intermediate said rods 16 and located in a plane somewhat therebelow are similar rods 17, similarly spaced, these rods being mounted on a frame structure 18 vertically adjustable relative to the frames 1. In this manner the actual spacing between adjacent ones of the rods 16 and 17 can be altered at will, this spacing being somewhat less than the width of the openings through the screens, whatever that may be, for the purpose hereinafter set forth.

A chute 19 is arranged at the end of the rod structure to carry off whatever reaches that end, while another chute 20 extends under said rods for the full length of the portion of the frames 1 fitted therewith.

Mounted on the frames 2 from end to end thereof are transversely extending rods 21. For a certain distance from the intake or starting end of said frames, which is that end under the screen-sheets, the rods 21 are evenly but somewhat closely spaced, while from there onto the other or discharge end of the frames the rods are still evenly spaced but are farther apart.

Similarly spaced and disposed co-operating rods 22 are positioned intermediate the rods 21 and in a plane slightly below the same, being mounted on a vertically adjustable frame structure 23 under the frame 2.

The frame 23, which is split or divided at the junction of the narrow with the widely spaced bars may be adjusted in any suitable manner, each portion individually by means for instance of bolts 24 secured in the frames 23 and projecting through the frames 2, with springs 25 about the bolts between the frames 2 and the bolt-heads thereabove.

This construction tends to cause the frames 23 to move upwardly. To counteract and still permit of this movement when desired set screws 26 are threaded through either frame, bearing against the adjacent face of the other frame. Thus the frames may be moved apart, or allowed to come together, enabling the direct spacing between the upper and lower rods being altered at will and as may be necessary.

This same means of adjustment may

of course be used in connection with the upper adjustable frame 18.

A chute or draper 27 extends under the frames 2 and 23 for the full length thereof, while a small transverse chute 28 is placed under the frames 23 where the close spacing of the bars 21 and 22 ends.

Another chute or draper 29 is placed at the discharge ends of the frames 23 to receive the clean nuts.

In operation, the hulled nuts, hulls, débris and meats, are dumped onto the intake end of the screen-sheet 7.

Due to the agitating or shaking of the structure, as previously described, the mass will shortly spread out over the sheet, and will move toward the opposite end of the apparatus.

The whole nuts of average size, as well as any meats, half hulls and small scraps generally, will pass through the openings 10 onto the rod structure below, the small stuff naturally passing through almost at the outset, and before travelling very far. The whole hulls, "sticktights" and excessively large nuts, unable to pass through said openings, will travel along the screen-sheets and finally pass onto the rods 16-17. These are spaced sufficiently far apart to enable the hulls to drop therebetween and onto the chute 20, but do not allow the sticktights and excessively large nuts to pass, and these are finally deposited onto the chute 19, from which the large nuts may be removed and the sticktights subjected to a further hulling treatment if desired.

At this point it is well to call attention to the fact that owing to the rods being alternately horizontally staggered or on different levels, a baffling effect is produced, causing the hulls to roll over, and between the rods instead of sliding along over the same, thus greatly facilitating the cleaning and separating action. It will be noted that although the space between the rods 16 and 17 is less in width than that of the openings 10, this space extends for the full length of the rods. It will also be remarked that although whole hulls are A or V shaped and as a unit are wider than the holes 10, each half hull in itself is thinner than the space between the rods. This allows the ends of the connected half hulls to drop between the rods, whose staggered arrangement, as above stated, causes said hulls to roll around and under the upper rods 16, and they can then drop into the chute 20.

The shape of the opening between the rods, allows the whole but split or opened hulls to pass therebetween, since each section of the hull is relatively thin. At the same time the much thicker and unbroken sticktights, etc., are retained, and the jerky or jumping reciprocating or shaking move-

ment of the entire structure causes the nuts to travel along the entire length of the structure.

Coming back to the starting point on the 5 lower rod structure, this carries at first everything but the unbroken hulls, stick-tights and oversized nuts.

The chaff and other small pieces of no 10 value included in this mass will at once drop between the closely spaced rods into the chute 27. These rods however cannot pass the actual nuts or meats of any size and these then travel along the closely spaced section to the end thereof, which is the beginning 15 of the widely spaced rod section, at which point the very small nuts, and any meats, drop through and onto the chute 28. Since the proportion of such small nuts and meats to the total bulk being handled is 20 always very small, it is not necessary that the chute 28 be very large or have any very great capacity. The whole and normal sized nuts cannot however pass between even the widely spaced rod section, and they therefore 25 travel along the same to be finally deposited in the chute 29, separated from everything else, as is desirable.

In the meantime, the half-hulls on the rods have all dropped therebetween and into 30 the chute 27.

By altering the level between any set of staggered rods, the space between adjacent rods on the different levels is of course altered, thus making this structure suitable for 35 any kind or size of nuts being handled.

From the foregoing description it will be readily seen that I have produced such a device as substantially fulfills the objects of the invention as set forth herein.

40 While this specification sets forth in detail the present and preferred construction of the device, still in practice such deviations from such detail may be resorted to as do not form a departure from the spirit 45 of the invention, as defined by the appended claims:

Having thus described my invention what I claim as new and useful and desire to secure by Letters Patent is:

50 1. An almond screening structure including a pair of upper screens, the mesh of one being narrower than that of the other, a pair of lower screens of different sized mesh from each other, the narrower mesh screen 55 of the latter being under the wider mesh screen of the upper screens, and means preventing the dropping of any matter from the upper narrow-mesh screen onto the screen below.

60 2. An almond screening structure including a pair of upper screens, the mesh of one being narrower than that of the other, a pair of lower screens of different sized mesh from each other, the narrower mesh screen

of the latter being under the wider mesh 65 screen of the upper screens, a chute at the outer end of the upper narrow-mesh screen, another chute extending lengthwise under the same, a third chute at the outer end of the lower wide mesh screen, and a fourth 70 chute extending lengthwise of both lower screens.

3. An almond screening structure including a pair of upper screens, the mesh of one being narrower than that of the other, a 75 pair of lower screens of different sized mesh from each other, the narrower mesh screen of the latter being under the wider mesh screen of the upper screens, means preventing the dropping of any matter from the 80 upper narrow-mesh screen onto the screen below, a transverse chute under the lower screens at the junction of the same, and a longitudinal chute under both said lower screens.

4. An almond screening structure including a pair of upper screens, the mesh of one being narrower than that of the other, a pair of lower screens of different sized mesh from each other, the narrower mesh screen 90 of the latter being under the wider mesh screen of the upper screens, and means for independently adjusting the size of mesh of the various screens.

5. An almond screening apparatus comprising 95 upper and lower screen structures, means for causing matter on the screens to travel from the forward to the rear end thereof; the forward portion of the upper screen structure to enable only the hulled nuts and anything smaller to pass therethrough, and the rear portion of said upper structure retaining only the unthreshed nuts; the lower screen structure having a mesh to retain only whole nuts, a chute to receive certain 100 of the matter passing through the lower screening structure, a transverse chute under said structure at a predetermined point intermediate its ends to receive any meats passing through said structure, and another 105 chute at the rear end of said lower structure to receive the whole nuts remaining thereon.

6. In an almond screening apparatus, a screening structure comprising a row of 110 horizontally spaced rods, an additional row of similarly arranged rods positioned intermediate the rods of the first row and in a plane lower than the same, and being vertically adjustable relative thereto; the spacing between any two rods in one row being greater than the width of a rod in the other row, whereby regardless of the relative horizontal alignment of the rods of the two rows, a space in a vertical plane will be left 115 between adjacent rods of both rows.

In testimony whereof I affix my signature.

LAURENCE L. MILLER.
